UNITED STATES PATENT OFFICE.

JOHN F. CUSHING, OF CHICAGO, ILLINOIS.

BREAKWATER.

Application filed January 29, 1921. Serial No. 441,025.

To all whom it may concern:

Be it known that I, JOHN F. CUSHING, a citizen of the United States, residing at Chicago, county of Cook, and State of Illinois, 5 have invented certain new and useful Improvements in Breakwaters, of which the following is a specification.

It is the object of my invention to provide a breakwater which shall be relatively 10 inexpensive, easy to construct and place, permanent and durable under the conditions to which constructions of the kind are commonly exposed. With this in view my improved breakwater comprises a suitable 15 foundation upon which is placed a series of hollow sections or cribs of concrete, keyed or interlocked together at their adjacent ends suitably filled and provided with a monolithic concrete cap extending over any 20 desired number of sections.

In the accompanying drawings and in the following specification I have illustrated and described a preferred embodiment of the invention, Fig. 1 representing in transverse 25 vertical section a breakwater and foundation embodying my invention; Fig. 2 a horizontal section through a portioin of such breakwater, the cribs being shown empty to better disclose the construction; Fig. 3 30 a longitudinal vertical section through one of the cribs and Fig. 4 an enlarged vertical transverse section of a detail. Each part is identified by the same reference character wherever it appears in the several views.

Referring first to Fig. 1 the foundation 35 for my improved breakwater is shown at 5 and may consist of quarry-run rock. The foundation is made of the required length and suitable height the latter depending on 40 local conditions being in some instances sufficient to bring the top of the foundation to within about 11 feet of the surface of the water after it has been leveled to receive the superstructure. Upon this foundation after 45 leveling are located a series of concrete cribs 6 which are interlocked when in position at their adjacent ends in a manner which will appear.

The cribs 6 are preferably made at some 50 convenient point on shore where they are allowed to season until the concrete has attained its maximum strength. Each crib comprises sloping side walls 7, 7 and end walls 8, 9, the whole structure being in the 55 form of a frustum of a wedge. Each crib is formed on the outside of one end with a

vertical rib or key 10 and on the outside of the other end wall with a mating groove or key-way 11. The concrete walls of the crib may be suitably reinforced, preferably 60 and as shown in the drawings by rods 12 lying in vertical planes the upper ends of which extend beyond the upper edges of the respective walls as at 13 for a purpose which will appear. The respective side walls are 65 formed with broad bases or sills 14 and wooden struts 15 spaced at suitable intervals longitudinally of the crib extend transversely of the same with their ends imbedded in the bases of the side walls. Obviously metal 70 beams could be employed but wooden beams answer the purpose being less expensive and thoroughly permanent since they are always immersed in water and at a considerable distance below the surface thereof. Tie rods 75 16 also connect the walls at suitable intervals being preferably arranged directly beneath the beams 15 and having their ends downturned as at 17 to secure a firm grip upon the concrete. 80

As heretofore stated the cribs are separately molded in advance and then are carried to the foundation on which they are to be placed being readily handled by ordinary marine equipment. A crib having a height 85 of 12½ feet, side walls 12 inches thick end walls 8 inches thick and with a base 15 feet by 11 feet and top 15 feet by 8 feet 8 inches weighs about 50 tons. After the cribs have been placed in position with the bases of 90 the side walls thereof resting upon the foundation and their end walls interlocked in the manner described quarry-run stone is used to fill the cribs to the top of the walls 95 thereof which in the specific construction described extend after being placed on the foundation about 1½ feet above the surface of the water. The filling rests partially upon the beams and partially directly on the foundation between the beams and the 100 crib structure is thus keyed to the foundation and slipping relative thereto is prevented. After the cribs have been placed in position and filled a cap 18 of concrete is 105 molded thereon extending preferably several feet above the top edges of the walls and filling and interlocking with the latter. This cap is preferably monolithic over several contiguous cribs and the sea side thereof is so inclined as to dissipate as far as possible the shock of the waves so that the tendency of the latter to move the breakwater is 110

minimized. The ends 13 of the reinforcing rods in the side walls extend into the body of the cap and bind it to the walls. After the cribs are in place riprap or covering 5 stone in sizes ranging from 300 pounds to 3 tons is laid on the sloping sides of the stone foundation thus completing the break-water.

My improved breakwater is substantially 10 permanent, the exposed surfaces being of stone or concrete and the few timbers used being submerged and not subject to deterioration. The breakwater proper while heavy enough for the purpose is light compared to 15 structures previously used and therefore it is necessary to use a relatively small amount of stone in the foundation. The sea face of the crib and cap can be so inclined as to reduce the shock of the waves to a minimum 20 and by reason of the inclination the sea when riding over the breakwater produces a downward thrust counteracting the tendency to overturn the structure. Except for the riprap of which a relatively small quantity 25 is used quarry-run stone of the cheapest character may be employed. Because of the character of the superstructure there is little danger of uneven settlement of the foundation after the former is in place and the 30 concrete forming the cap may be made sub-

stantially impervious to water and hence weatherproof. Moreover in case of damage to any part of the construction the damaged crib may be removed and a new crib section inserted at a relatively low cost. 35

By the use of these crib sections which may be filled with smaller and cheaper stone the use of the expensive heavier stone heretofore required in the breakwaters of this kind for the portions more exposed to the 40 violence of the waves is obviated.

I claim:

1. A break-water comprising a series of monolithic concrete cribs composed of side and end walls, the end walls having interlocking projections and recesses, filling in said cribs, and a monolithic concrete cap extending over a plurality of said cribs and partially into the interior thereof to maintain them interlocked. 60

2. A crib for forming breakwaters, comprising integral concrete side and end walls, the former being formed with enlarged bases, spaced beams extending across the crib near the bottom thereof, the ends of the beams being imbedded in but not extending through the side walls, and tie-rods connecting the side walls and arranged beneath said beams.

JOHN F. CUSHING.
